UNITED STATES PATENT OFFICE.

HENRY F. SCHMIDT, OF SWARTHMORE, PENNSYLVANIA, ASSIGNOR TO WESTINGHOUSE ELECTRIC AND MANUFACTURING COMPANY, A CORPORATION OF PENNSYLVANIA.

CONDENSER INSTALLATION.

Application filed December 28, 1920. Serial No. 433,683.

My invention relates to condenser installations and particularly to apparatus for withdrawing condensate from a condenser and for eliminating the difficulties ordinarily encountered with apparatus employed for this purpose.

Condensate is usually withdrawn from a condenser by means of either a rotary or a reciprocating condensate pump. The rotary pump has a number of advantageous features which render it more desirable than the ordinary reciprocating pump. One objection however, is that the rotary condensate pump must be placed a sufficient distance below the condenser to provide the necessary submergence. This is sometimes difficult to accomplish, especially in marine installations where the head room is materially limited. In addition to this, the pump is necessarily located in an almost inaccessible place and consequently it is difficult to give it proper care and attention and to repair it in case of accident.

An object of this invention is to provide a new and improved apparatus for withdrawing water of condensation or other liquids from a condenser.

A further object is to produce a new and improved condenser installation in which the condensate pump may be located in any suitable place and yet have the proper submergence.

These and other objects which will be made apparent throughout the further description of my invention are attained by means of apparatus embodying the features of my invention herein described, and illustrated in the drawing accompanying and forming a part hereof.

The single figure of the accompanying drawing is a diagrammatic sectional view of a condenser installation embodying the features of my invention.

In the drawing, I have illustrated a condenser 5 having at its top an inlet port 6 for fluids to be condensed, hereinafter called steam, and at its bottom a well 7 in which the condensate collects. Extending through the condensate well 7, I show an ejector 8, comprising as illustrated, a nozzle 9, a combining tube 10 and a diffuser 11 arranged in the usual manner. The nozzle 9 is adapted to receive motive fluid from a conduit 12 and to discharge it at high velocity into a combining tube 10 which, as shown, is open to

the condensate well 7. Around the adjacent ends of the combining tube 10 and the diffuser 11, I show an overflow chamber 13, which as illustrated, is provided with a pipe 14 extending upward from the condensate well 7 into the interior of the condenser 5.

As shown, the ejector 8 is adapted to discharge into a conduit 15 which leads to a tank or condensate receiver 16 located somewhat above the horizontal center line of the condenser 5. I illustrate cooling tubes 17 as extending through the tank 16 for the purpose of cooling the fluids discharged into the tank by the ejector 8. The tank 16 is also provided with an overflow or vent pipe 18 which connects it with the interior of the condenser 5. A baffle 19 is shown for preventing condensate from overflowing into the condenser 5 except when the supply of condensate is more than sufficient to keep the cooling tubes 17 submerged.

As illustrated, the tank 16 is connected with the ejector 20 by means of a pipe 21. The ejector 20 is located on a lower level than the tank 16 so as to receive the proper submergence. As shown, the ejector 20 is provided with a nozzle 22, an inlet chamber 23, a combining tube 24, a diffuser 25 and an overflow chamber 26, all arranged in the usual manner. I show the overflow chamber 26 as connected with the tank 16 by means of a conduit 27.

In operation the condensate from the condenser 5 collects in the condensate well 7, is entrained by the jet of steam from the nozzle 9 and is carried into and through the combining tube 10 and the diffuser 11. In the diffuser 11, a part of the velocity energy of the fluids is converted into pressure energy so that the fluids are discharged into the tank 16 against the pressure due to the head between the tank 16 and the ejector 8. When the ejector 8 is started, it will be understood that the fluids will at first be discharged through the overflow pipe 14 until their velocity through the ejector is sufficient to cause them to be discharged against the pressure in the discharge pipe 15.

In the apparatus illustrated the condensate is cooled in the tank 16 by the cooling tubes 17 and is then delivered to the ejector 20 by means of the pipe 21. The difference in elevation between the ejector 20 and the tank 16 insures the proper submergence for the ejector. The condensate is entrained in

the ejector 20 and is discharged in the usual manner. The cooling of the condensate in the tank causes it to be more efficiently entrained in the ejector 20 and consequently 5 the efficiency and operating characteristics of the ejector are improved.

In the apparatus illustrated, the ejector 8 may be termed a lifting ejector, as its function is to merely elevate the condensate 10 to the tank 16. The ejector 20 as shown, is the main condensate pump and discharges the condensate against atmospheric pressure plus the pressure due to the head existing 15 in the discharge system.

15. In the drawing the overflow chamber 26 of the ejector 20 is connected with the tank 16, but it will be understood that it may be connected directly with the interior of the condenser 5 or with any other region of relatively 20 low pressure. It will also be understood that any type of pump may be employed in place of the ejectors shown.

An advantage of an installation such as that illustrated is that the ejector 20 or condensate pump may be placed where it is 25 easily accessible. A further advantage is that the head room is greatly reduced as compared with the head room required when the condensate pump is located directly below 30 the condenser in the usual manner. Furthermore, the head of the inlet to the condensate pump may be considerable, due to the difference in elevation of the condensate pump and the tank 16, without detrimentally 35 affecting the head room required for the installation.

While I have shown my invention in but one form, it will be obvious to those skilled 40 in the art that it is not so limited, but is susceptible of various other changes and modifications, without departing from the spirit thereof, and I desire, therefore, that only such limitations shall be placed thereupon as are imposed by the prior art or as 45 are specifically set forth in the appended claims.

What I claim is:

1. In combination with a condenser, first and second stage ejector apparatus for removing condensate from the condenser, a cooler interposed between the first and second stage ejectors, and overflow means associated with the second stage ejector and discharging into the cooler.
5. In combination with a condenser, first and second stage ejector apparatus for removing condensate from the condenser, a cooler interposed between the first and sec-

ond stage ejectors, overflow means associated with the second stage ejector and discharging into the cooler, and overflow means associated with the cooler and discharging into the condenser.

3. In combination with a condenser, first and second stage fluid translating means for removing condensate from the condenser, a cooler interposed between the first and second stage fluid translating means, and overflow means associated with the second stage fluid translating means.

4. In combination with a condenser, first and second stage fluid translating means for removing condensate from the condenser, a cooler interposed between the first and second stage translating means, overflow means associated with the second stage fluid translating means and discharging into the cooler, and overflow means associated with the cooler and discharging into the condenser.

5. In combination with a condenser and a hotwell for receiving condensate from the condenser, a first stage ejector disposed at substantially the same elevation as the hotwell for removing condensate therefrom, a second stage ejector connected in series with the first stage ejector and a cooler interposed between the ejectors.

6. In a condenser comprising a shell having an inlet for condensable gases and a hotwell for receiving condensate, the combination of fluid translating means within the hotwell, said means having an inlet for receiving condensate and an overflow within the hotwell, means within the hotwell providing a chamber enclosing said overflow, and a passage from said chamber to a region of relatively low pressure within the condenser, said passage being entirely within the hotwell and the shell.

7. In a condenser comprising a shell having an inlet for condensable gases and a hotwell for receiving condensate, the combination of fluid translating means within the hotwell, said means having an inlet for receiving condensate and an overflow within the hotwell, and means entirely within the hotwell and the shell for affording direction communication between the overflow and a region within the shell above that level to which condensate might rise in the normal 105 operation of the condenser.

In testimony whereof, I have hereunto subscribed my name this 21st day of December, 1920.

HENRY F. SCHMIDT.
